ATTORNEYS

UNITED STATES PATENT OFFICE.

JOHN WILLIAM CAUTHEN, OF KANNAPOLIS, NORTH CAROLINA.

STOP MOTION FOR SPINNING FRAMES.

Application filed February 15, 1922. Serial No. 536,732.

To all whom it may concern:

Be it known that I, JOHN WILLIAM CAUTHEN, a citizen of the United States, and a resident of Kannapolis, in the county of 5 Cabarrus and State of North Carolina, have invented certain new and useful Improvements in Stop Motions for Spinning Frames, of which the following is a specification.

My invention relates to improvements in 10 spinning frames, but more particularly to stop motion mechanism therefor, and it consists in the construction, combination and mode of operation herein described and claimed.

15 One of the objects of the invention is to provide a stop motion mechanism for spinning frames which will prevent over-filling of the bobbins.

A further object of the invention is to 20 provide stop motion mechanism which will lock the frame when it comes into operation, so that the operative can doff the bobbin without danger of injury by a re-starting of the spinning frame.

25 Other objects and advantages will appear in the following specification, reference being had to the accompanying drawing, in which:

Fig. 1 is a perspective view illustrating 30 the elements of the improved stop motion mechanism, and

Figs. 2, 3 and 4 are sections on the line 2—2, 3—3 and 4—4 of Fig. 1 respectively.

The purposes of the invention may be 35 briefly related so that the reader may become acquainted with the use to which it is put. As stated in the objects of the invention, the improved stop motion mechanism prevents the bobbins of a spinning 40 frame from becoming over-filled, and since the stop motion mechanism is made to "knock off" regularly, each bobbin will contain precisely the same amount of yarn. This precision of operation effects a great 45 saving of yarn by virtue of the fact that the bobbins are not permitted to become over-filled.

The locking of the spinning frame when 50 the stop motion mechanism functions, enables the operative to doff the filled bobbins without danger of injury by a restarting of the spinning frame.

The construction of the invention comprises a latch 1 with a holding shoulder 2 on the under side and a lock shoulder 3 on one side. The shoulder 2 normally engages

a bracket 4 and thus holds the latch 1 retracted against the tension of the spring 5. The bracket 4 is fixed at F (Fig. 4) on a convenient part of a spinning frame. A 60 stud 6 is also fixed to a convenient part of the frame. It is to this stud that the spring 5 has connection through a link 7.

The latch 1 has a slot 8 in which a bolt 9 is fixed as shown in Fig. 2. It is in the 65 end of this bolt that a shifter bar 10 is fixed so as to move with the latch 1 when released from the bracket 4. The bar 10 carries a yoke 11 on the far end for the purpose of shifting the belt B from the fast 70 pulley 12 to the loose pulley 13.

The raising of a lift rod 14 disengages the shoulder 2 of the latch 1 from the bracket 4 and enables the spring 5 to contract and cause the shifting of the belt B to 75 the loose pulley 13 through the medium of the shifter bar 10. The rod 14 is pivoted at 15 in a bearing 16 which is fixed on the spinning frame. A support 17 guides the free end of the rod 14. A lift stem 19 80 engages the under side of the rod 14, and at the lowermost extremity carries an adjustable screw 18 which is adapted to be engaged by a lever 21.

A bracket 20 guides the lift stem 19. The 85 lever 21 causes the moving of the stem 19 in its bracket 20 and thus causes the raising of the lift rod 14 with the result mentioned above.

The lever 21 is actuated by the rocker 90 shaft 22 which is one of the main operating parts of the spinning frame. This shaft operates at predetermined times, to lift the lever 21, strike the screw 18, raise the rod 19, move the rod 14 on its pivot 15 and so release 95 the latch 1 from the bracket 4 so that the spring 5 may pull the latch over toward the right in Fig. 1 and cause the shifting of the belt B onto the loose pulley 13. The movement of the latch 1 and rod 10 under the 100 influence of the spring 5 is limited by the engagement of the shoulder 3 with the adjacent side of the bracket 4.

I claim:—

1. Stop motion mechanism comprising a 105 latch having a shoulder and a slot, means for pulling the latch in one direction, a bracket engageable by said shoulder to resist the tendency of said pulling means, a shifter bar having a yoke for shifting a belt 110 from a fast to a loose pulley, means serving as a mounting for the shifter bar on the

latch including an extension which is adjustable in the slot of said latch, a pivoted rod adapted to lift the latch shoulder from the bracket to permit operation by said pulling means, a lifter rod engaging said pivoted rod, and a lever carried by a rock shaft of a spinning frame adapted to periodically engage the lifter rod.

2. Stop motion mechanism comprising a latch having a shoulder and a slot, means for pulling the latch in one direction, a bracket furnishing partial support for the latch being adapted to be engaged by the shoulder to resist said pulling means, a shifter bar having a yoke for shifting a belt from a fast to a loose pulley, a bolt in which the shifter bar is adjustably fixed including a reduced portion occupying the slot, means on said reduced portion by which adjustments of the bolt in the slot may be fixed, a rod adapted to lift the latch shoulder from the bracket, means on which one end of said rod is pivoted, means adjacent to the other end for guiding the rod, a lifter rod engaging said pivoted rod, means support-

ing said lifter rod, a lever carried by a rock shaft of a spinning frame adapted to periodically engage the lifter rod, and adjustable means on the engageable end of the lifter rod to vary the place of engagement. 30

3. Stop motion mechanism comprising a latch which has a shoulder on one edge and a slot in one end, means attached to the latch to pull it one way, a bracket in which the latch may slide but in which such sliding is checked by the engagement of said shoulder, a shifter rod situated beside the latch and having a yoke for shifting a belt from a fast to a loose pulley, means which serves as a carrier for the shifter rod, means by which said carrier means is adjustable in said slot so as to vary the longitudinal position of the shifter rod in respect to the latch, and means to lift the latch and rod simultaneously thereby to disengage said shoulder and permit the latch and rod to move together under the influence of said pulling means. 40 45

JOHN WILLIAM CAUTHEN.
